CONVERSION OF HYDROCARBONS

Gustav Egloff, Chicago, Ill., assignor to Universal
Oil Products Company, Chicago, Ill., a corpora-
tion of Delaware

Application April 3, 1941, Serial No. 386,603

7 Claims. (Cl. 196—10)

This invention in general relates to the conversion of hydrocarbon oil and more particularly to a combination of inter-related and cooperative steps whereby maximum utilization of all components of not only the charging stock but also of the intermediate conversion products is obtained. According to the features of this process, selected fractions are individually treated under optimum conditions for the maximum conversion thereof and, in addition, the invention provides for the utilization of more highly heated products to assist in the conversion and vaporization of the less highly heated products.

The primary charging stock, which may comprise an oil boiling above the range of gasoline, is separated into relatively light and relatively heavy fractions. Each fraction is separately heated under independently controlled cracking conditions. Simultaneously, a secondary charging stock, which may comprise an oil boiling substantially within the range of gasoline, is also separately heated under independently controlled reforming conditions. The olefinic constituents of the gaseous products of the process are polymerized in the presence of suitable catalyst to produce additional quantities of high octane gasoline. As one primary feature of the invention, the residual gases remaining after the polymerization operation, which consist mostly of propane and butane but may also include some higher and lower boiling fractions, as well as any unconverted olefinic constituents, are separately heated under more severe independently controlled conditions to effect interaction between these gases for the production of additional quantities of liquid products. This interaction may include various reactions as, for example, cracking, dehydrogenation, polymerization, alkylation, condensation, etc. Provision is also made for supplying the less reactive gaseous products of the process to the same heating zone. These less reactive gases include hydrogen, methane, ethane, ethylene, etc.

In addition, as another feature of the invention, the highly heated products are supplied to the lower portion of the coke chamber to assist conversion of the residual liquid therein to coke and also to assist liberation and separation of the vaporous conversion products from the coking zone. Another advantage to this operation is the production of a less volatile coke as one of the main products of the process.

As a further feature of the invention, the gasoline produced in the thermal cracking and coking steps is blended with the gasoline produced in the

polymerization step and the mixture is subjected to common stabilization whereby to produce a final product of the desired vapor pressure and of high octane value.

5 In one specific embodiment the invention comprises fractionating a primary charging stock in the presence of intermediate conversion products to separate selected fractions comprising a relatively heavy combined feed, a relatively light combined feed, gasoline boiling range fractions, a fraction consisting predominantly of 3- and 4-carbon atom molecules, and a lighter gas fraction, separately cracking said relatively heavy and light combined feeds under independently controlled conditions, simultaneously separately heating a secondary charging stock, introducing all of the heated products to a coke chamber, fractionating the vaporous conversion products evolved in the coke chamber in the presence of 10 the primary charging stock, as previously described, polymerizing the fraction consisting predominantly of 3 and 4 carbon atom molecules, separating from the polymerization products the unconverted gases, separately heating these gases 15 under independently controlled conditions, introducing the last mentioned heated stream into the lower portion of the coke chamber, combining the previously separated gasoline products of the cracking and coking operation with the gasoline produced in the polymerization step and subjecting the mixture to common stabilization to produce a final gasoline product of the desired vapor pressure and of high anti-knock value.

20 The term combined feed, as used throughout the specification, is intended to designate the mixture of charging stock and intermediate conversion products being supplied to the various heating coils of the process.

25 It is not intended to unnecessarily limit the present invention to the complete combination of steps shown in the drawing and described in the specification. Various lesser combinations which are new in the present state of prior art are also comprised within the scope of the present invention. These lesser combinations may omit, for example, the separate reforming step in one case, or in another case the commingling of the less reactive process gases with the residual paraffinic gases being supplied to the separate heating treatment.

30 The accompanying diagrammatic drawing to further illustrate the present invention is essentially a flow diagram and is not drawn to any specific scale.

35 Referring to the drawing, the primary charg-

ing stock, which may comprise any oil of higher boiling range than gasoline, including crude oil, topped crude, fuel oil, gas oil, kerosene, or the like, is introduced to the process, preferably in at least a partially heated condition, through line 1 and valve 2 to pump 3 wherefrom it is supplied through line 4 and valve 5 to fractionator and separator 6. The primary charging stock is separated therein, together with vaporous conversion products supplied thereto, as will subsequently be described, into selected fractions comprising a relatively heavy combined feed, a relatively light combined feed, a fraction boiling substantially within the range of gasoline, a fraction consisting predominantly of 3 and 4 carbon atom molecules, and a lighter gaseous fraction.

Fractionator and separator 6 is illustrated, for the sake of simplicity, as one zone. It is understood that this may comprise separate zones, such as one or more separators, fractionators, condensing means, receivers, accumulators, etc. In addition, the conventional method of returning a portion of the condensed overhead product to serve as a cooling and refluxing medium has been omitted for the sake of simplicity. It is further understood that the fractionators and separators may contain the conventional baffles, bubble trays, etc.

The heavy combined feed is withdrawn from chamber 6 through line 7 and valve 8 to pump 9 wherefrom it is supplied through line 10 and valve 11 to heating coil 12 in furnace structure 13. The oil is preferably heated in coil 12, depending upon its characteristics, to a temperature of 850-1050° F. at a pressure of substantially atmospheric to 500 pounds or more. The heated products are withdrawn through line 14 and valve 15 and are supplied either through line 16 and valve 17 to coke chamber 18 or through line 19 and valve 20 to coke chamber 21.

Simultaneously, a secondary charging stock, which preferably comprises a distillate of substantially gasoline boiling range, is introduced through line 22 and valve 23 to pump 24 wherefrom it is supplied through line 25 and valve 26 to heating coil 27 in furnace structure 28. The secondary charging stock may comprise either material boiling up to substantially 400° F. or it may also include higher boiling fractions such as those of kerosene, or the like. If the primary charging stock comprises a topped crude, the secondary charging stock may comprise the straight-run gasoline fractions separated from the original crude oil. In certain instances, the secondary charging stock may have an end-boiling point of less than 400° F. The oil supplied to heating coil 27 is heated therein to a temperature of 950-1150° F. at a pressure of atmospheric to 1000 pounds or more. The heated products are supplied through line 29 and valve 30 and either through line 16 and valve 17 to coke chamber 18 or through line 19 and valve 20 to coke chamber 21.

The light combined feed is withdrawn from fractionator and separator 6 through line 31 and valve 32 to pump 33 wherefrom it is supplied through line 34 and valve 35 to heating coil 36 in furnace structure 37. The light combined feed is heated in coil 36 to a temperature of 950-1150° F. at a pressure of atmospheric to 1000 pounds or more. The heated products are withdrawn through line 38 and valve 39 and are preferably supplied through line 40 and valve 41 to the lower portion of coke chamber 18 or through

line 42 and valve 43 to the lower portion of coke chamber 21. Alternatively, when desired, the heated products from coil 27 may be supplied to the lower portion of the coke chambers and the heated products from coil 36 may be supplied to the upper portion of the coke chambers. In certain instances, it may be desirable to supply the heated products from both coils 27 and 36 to the lower portion of the coke chambers. In any event, it is preferable to introduce the more highly heated products to the lower portion of the coke chambers and this will depend upon the characteristics of the oil streams being supplied to these coils. The products supplied to the lower portion of the coke chambers serve two important purposes; namely, the furnishing of additional heat to assist the coking operation and also to assist in the separation within and withdrawal from the coke chambers of the vaporous conversion products.

Although two coking chambers are shown in the drawing, it is understood, of course, that one or three or more may be employed. When two or more are employed, they are preferably alternately operated so that one or more chambers may be in service while coke from the other, or others, is being removed. Lines 44 and 46, controlled by valves 45 and 47, respectively, are conventional and are provided for the purpose of either introducing steam or other materials to assist in cleaning the coke chambers or for the withdrawal of any liquid condensate at any time from the coke chambers. The vaporous products evolved in the coke chambers are withdrawn therefrom through line 48 and valve 49 or through line 50 and valve 51 and are supplied through line 52 to fractionator and separator 6, wherein they undergo fractionation and separation in a commingled state with the primary charging stock, as previously described.

The fraction boiling substantially within the range of gasoline is withdrawn from fractionator and separator 6 through line 53 and valve 54 to pump 55 wherefrom it is supplied through line 56 and valve 57 to stabilizer 58. The operation of the stabilizer will be subsequently described.

The gaseous fractions consisting predominantly of 3 and 4 carbon atom molecules are withdrawn from column 6 through line 59 and valve 60 to pump 61 wherefrom they are supplied through line 62 and valve 63 to a polymerization operation. Polymerization of the olefins may be effected in the presence of any suitable catalyst or by known non-catalytic methods. The catalysts, when employed, are well-known and a few of the many which may be mentioned include solid phosphoric acid, acid treated clays, liquid phosphoric or sulfuric acids, etc. The drawing illustrates one embodiment in which the catalyst is a solid material packed in a reaction zone, in which case the olefins in line 62 are supplied through valve 63 to heating coil 64 in furnace structure 65. The gases are heated in coil 64 to the desired temperature and under the desired pressure, depending upon the type of catalyst being employed. With solid phosphoric acid catalysts, temperatures of 150-550° F. and pressures of 100 to 1500 pounds, or more, may be employed. With liquid sulfuric acid, temperatures of 80-200° F. and preferably sufficient pressure to maintain liquid phase conditions are employed. The heated products are supplied through line 66 and valve 67 to catalyst-containing reactor 68. The polymerization products are withdrawn

therefrom through line 69 and valve 70 and are supplied to stabilizer 58.

The products supplied to stabilizer 58 are fractionated to produce a gasoline product of the desired vapor pressure and of relatively high octane number, which product may be withdrawn through line 71 and valve 72 to storage or elsewhere, as desired. The stabilizer operates in the conventional manner, which is at pressures of 100 to 300 pounds but, as a feature of the invention, the gasoline produced in the cracking and coking operation is admixed with the gasoline produced in the polymerization operation and the mixture is subjected to stabilization in commingled state. The exact temperatures employed in the stabilization operation will depend upon the vapor pressure desired in the final gasoline product, which vapor pressure will in turn depend upon the season of the year and the market requirements. If any components of the material supplied to the stabilizer are of higher boiling range than that desired in the final gasoline, they may be separated in stabilizer 58 and removed therefrom through line 73 and valve 74. This material may be removed from the process or may be returned to any point in the system for further conversion. For the sake of simplicity, the stabilization operation is shown in the drawing as comprising a single column but may comprise two or more columns, each containing the conventional bubble trays, baffles, and the like. I have also omitted the conventional condensers, receivers, accumulators, as well as the return of a portion of the condensate from the overhead products of the stabilizer back to the stabilizer to serve as a cooling and refluxing medium therein. These steps are conventional and are well-known in the art so there is no need to complicate the drawing by including them therein.

The gaseous products remaining unconverted in the polymerization step and consisting predominantly of paraffinic hydrocarbons are withdrawn from stabilizer 58 through line 75. A portion may be removed from the process through line 76 and valve 77, but at least a portion of these gases is supplied through valve 78, line 87, pump or compressor 88, line 89 and valve 90 to heating coil 79 in furnace structure 80. The light gases separated in fractionator and separator 6 are removed therefrom through line 81 and all or a portion may be removed from the process through line 82 and valve 83. In some instances at least a portion is supplied through valve 84, line 87, pump or compressor 88, line 89 and valve 90 to heating coil 79. The gases supplied to coil 79 may be heated therein to a temperature of 1100-1400° F. at atmospheric to 5000 pounds or more. These conditions are preferably regulated to effect interaction between these gases and also to provide them in the highly heated state so that, when they are supplied through line 85 and valve 86 and either line 40 and valve 41 to coke chamber 18 or line 42 and valve 43 to coke chamber 21, they will supply additional heat to assist in the coking operation. Under certain circumstances, the process may be operated so that at least a portion of the interaction between the gases and the vaporous products of the process will be effected within the coke chambers. According to the present process, a less volatile coke product is obtained than is normally produced in the conventional coking operations. In addition to supplying a product which is more desirable in certain instances, the

operation provides a greater amount of vaporous material which may be subsequently condensed and subjected to additional cracking for the production of further quantities of gasoline.

- 5 Although the various heating coils are shown as positioned in separate furnace structures, it is, of course, within the scope of the invention to include two or more within a single furnace structure.
- 10 It is thus seen by the cooperative and inter-dependent steps of the present process, the various components of the oil and gases are subjected to conversion under optimum conditions to produce maximum yields of the desired final products of the process.
- 15 As an example of one specific operation, which may be conducted according to the present process, the primary charging stock may comprise topped crude and is separated in the fractionator 20 and separating zone into relatively light and heavy fractions. The heavy fraction may be heated to a temperature of 975° F. at 200 pounds. The light fraction may be heated to a temperature of 1050° F. at a pressure of 500 pounds. A secondary naphtha charging stock may be heated to a temperature of 1050° F. at a pressure of 500 pounds. The gaseous products supplied to heating coil 79 may be heated to a temperature of 1200° F. The 3 and 4 carbon atom molecules may 30 be polymerized in the presence of solid phosphoric acid catalyst at a temperature of 475° F. and at a pressure of 1000 pounds. An operation of this type may produce, based on the charging stocks, approximately 64% of final gasoline distillate of approximately 77 octane number and approximately 26% of low volatile coke.

I claim as my invention:

1. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a 40 C₃-C₄ fraction and light gas fraction, heating said selected heavy fraction to a cracking temperature, heating said selected light fraction to an independently controlled more severe cracking temperature, introducing the heated fractions 45 into a coke chamber, polymerizing the olefinic constituents of said C₃-C₄ fraction, admixing said fraction boiling substantially within the range of gasoline with the products from the polymerization step, subjecting the mixture to 50 stabilization to separate unconverted gases, heating said unconverted gases to an elevated temperature in a separate heating zone and introducing them into the coke chamber, and subjecting the vaporous conversion products evolved 55 in the coke chamber to fractionation in commingled state with said hydrocarbon oil, as previously set forth.
2. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a 60 fraction consisting predominantly of 3 and 4 carbon atom molecules and a lighter gaseous fraction, heating said selected heavy fraction to a cracking temperature, heating said selected light fraction to an independently controlled more severe cracking temperature, introducing 65
- 70
- 75

the heated fractions into a coke chamber, polymerizing the olefinic constituents of said fraction consisting predominantly of 3 and 4 carbon atom molecules, admixing said fraction boiling substantially within the range of gasoline with said products from the polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone, introducing the last mentioned reaction products into the coke chamber, and subjecting vaporous conversion products evolved in the coke chamber to fractionation in commingled state with said hydrocarbon oil, as previously set forth.

3. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a fraction consisting predominantly of 3 and 4 carbon atom molecules and a lighter gaseous fraction, heating said selected heavy fraction to a cracking temperature, heating said selected light fraction to independently controlled more severe cracking temperature, simultaneously heating a hydrocarbon oil of substantially gasoline boiling range to a reforming temperature, introducing the heated materials into a coke chamber, polymerizing the olefinic constituents of said fraction consisting predominantly of 3 and 4 carbon atom molecules, admixing said fraction boiling substantially within the range of gasoline with the products from said polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone and introducing the reaction products therefrom into the coke chamber, and subjecting vaporous conversion products evolved in the coke chamber to fractionation in commingled state with said hydrocarbon oil, as previously set forth.

4. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a fraction consisting predominantly of 3 and 4 carbon atom molecules and a lighter gaseous fraction, heating said selected heavy fraction to a cracking temperature, heating said selected light fraction to independently controlled more severe cracking temperature, introducing the heated fractions into the upper portion of a coke chamber, polymerizing the olefinic constituents of said fraction consisting predominantly of 3 and 4 carbon atom molecules, admixing said fraction boiling substantially within the range of gasoline with the products from said polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone and introducing the reaction products into the lower portion of the coke chamber, and subjecting vaporous conversion products evolved in the coke chamber to fractionation in commingled state with said hydrocarbon oil, as previously set forth.

and introducing reaction products therefrom into the lower portion of the coke chamber, and subjecting vaporous conversion products evolved in the coke chamber to fractionation in commingled state with said hydrocarbon oil, as previously set forth.

5. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a fraction consisting predominantly of 3 and 4 carbon atom molecules and a lighter gaseous fraction, heating said selected heavy fraction to a cracking temperature, heating said selected light fraction to independently controlled more severe cracking temperature, simultaneously heating a hydrocarbon oil of substantially gasoline boiling range to a reforming temperature, introducing the heated materials into the upper portion of a coke chamber, polymerizing the olefinic constituents of said fraction consisting predominantly of 3 and 4 carbon atom molecules, admixing said fraction boiling substantially within the range of gasoline with the products from said polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone and introducing the reaction product into the lower portion of the coke chamber, and subjecting vaporous conversion products evolved in the coke chamber to fractionation in commingled state with said hydrocarbon oil, as previously set forth.

6. A process for the conversion of hydrocarbons which comprises fractionating a hydrocarbon oil in commingled state with vaporous conversion products produced in the process as hereinafter set forth, to separate a selected heavy fraction, a selected light fraction, a fraction boiling substantially within the range of gasoline, a fraction consisting predominantly of 3 and 4 carbon atom molecules and a lighter gaseous fraction, heating said selected heavy fraction to a cracking temperature, introducing the heated stream into the upper portion of a coke chamber, heating said selected light fraction to independently controlled more severe cracking temperature, introducing the heated stream into the lower portion of the coke chamber, polymerizing the olefinic constituents of said fraction consisting predominantly of 3 and 4 carbon atom molecules, admixing said fraction boiling substantially within the range of gasoline with the products from said polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone and introducing the reaction products into the lower portion of the coke chamber, and subjecting vaporous conversion products evolved in the coke chamber to fractionation in commingled state with said hydrocarbon oil, as previously set forth.

7. A process for the conversion of hydrocarbons which comprises fractionating a hydrocarbon oil in commingled state with vaporous conversion

products produced in the process as hereinafter set forth, to separate a selected heavy fraction, a selected light fraction, a fraction boiling substantially within the range of gasoline, a fraction consisting predominantly of 3 and 4 carbon atom molecules and a lighter gaseous fraction, heating said selected heavy fraction to a cracking temperature, introducing the heated stream into the upper portion of a coke chamber, heating said selected light fraction to an independently controlled more severe cracking temperature and introducing it into the lower portion of the coke chamber, polymerizing the olefinic constituents of said fraction consisting predominantly of 3 and 4 carbon atom molecules, admixing said frac-

tion boiling substantially within the range of gasoline with the products from said polymerization step, subjecting the mixture to stabilization in commingled state, admixing said lighter gaseous fraction with the normally gaseous products remaining unconverted in the polymerization step and evolved in said stabilization operation, reacting the mixture of gases in a separate heating zone and introducing the reaction products into the upper portion of the coke chamber, and subjecting vaporous conversion products evolved in the coke chamber to fractionation in commingled state with said hydrocarbon oil, as previously set forth.
